UNITED STATES PATENT OFFICE.

GEORGE H. THOMAS, OF DAYTON, OHIO.

DESIGN FOR A TAMPING-TOOL.

SPECIFICATION forming part of Design No. 25,013, dated December 24, 1895.

Application filed October 30, 1895. Serial No. 567,445. Term of patent 7 years.

To all whom it may concern:

Be it known that I, GEORGE H. THOMAS, a citizen of the United States, residing at Dayton, in the county of Montgomery and State of Ohio, have invented and produced a new and original Design for a Tamping-Tool; and I do declare the following to be a full, clear, and exact description of the same, reference being had to the accompanying drawings, 10 forming a part thereof.

Figure 1 is a perspective view of a tamping-tool, showing my design. Fig. 2 is a sectional view on the line $x-x$ of Fig. 1, but reduced in size.

15 The leading feature of said design consists of a block having four sides, two of which, a , are perpendicular, and the remaining two sides b incline from the lower extremity upward toward the vertical center, but terminate a sufficient distance from the center to provide a horizontal plane c parallel to and ap-

proximately one-third the width of the base d . From said upper horizontal surface c there is extended a cylindrical portion e , the upper half of which is hollow and adapted to form 25 a socket for the reception of a handle, which is shown as broken off, but which forms no part of the design. A horizontal section taken at any point between the base and the apex of said block will present the rectangular outline shown in Fig. 2.

Having described my newly-designed tamping-tool, I claim—

The design for a tamping-tool herein shown and described. 35

In testimony whereof I affix my signature in presence of two witnesses.

GEORGE H. THOMAS.

Witnesses:

R. J. McCARTY,

C. I. LONGENECKER.
